FIG. 1.

FIG. 2.

Inventor:

Charles I McClelland;

By Robert D. Fawcett,

Attorney

UNITED STATES PATENT OFFICE.

CHARLES I. McCLELLAND, OF RICHMOND, INDIANA, ASSIGNOR TO McCLELLAND CASKET HARDWARE COMPANY, OF RICHMOND, INDIANA, A CORPORATION OF INDIANA.

DESIGN FOR A CASKET HANDLE.

Application filed January 5, 1928. Serial No. 24,759. Term of patent 3½ years.

To all whom it may concern:

Be it known that I, CHARLES I. McCLELLAND, a citizen of the United States, residing in the city of Richmond, in the county of Wayne and State of Indiana, have invented a new, original, and ornamental Design for a Casket Handle, of which the following is a specification, reference being had to the accompanying drawing, forming a part thereof.

Figure 1 is a front face elevation of a casket handle showing my new design. And Figure 2 is a cross section of the same, as taken on the line 2—2 of Figure 1, and as looking in the direction indicated by the arrows in connection with said line.

What I claim is:

The ornamental design for a casket handle substantially as shown.

In testimony whereof I have hereunto subscribed my name, December 31st, 1927.

CHARLES I. McCLELLAND.
